IMPELLER HAMMER FOR A SILO UNLOADER OR THE LIKE

Floyd E. Buschbom, Rte. 1, Long Lake, Minn.

Filed Feb. 1960, Ser. No. 59,537

Term of patent 14 years

(Cl. D55—1)

FIG. 1

FIG. 3

FIG. 2

FIG. 4

FIG. 5

FIG. 6

FIG. 7

FIG. 1 is a top plan view of an impeller hammer for a silo unloader or the like showing my new design;

FIG. 2 is a side elevation thereof taken from the bottom of FIG. 1;

FIG. 3 is an end elevation taken from the right of FIG. 1;

FIG. 4 is an end elevation taken from the left of FIG. 1;

FIG. 5 is a bottom plan view of the impeller hammer.

FIG. 6 is a perspective view of the impeller hammer taken from the upper right of FIGURE 2 and drawn to a larger scale than that figure; and

FIG. 7 is a perspective view of the impeller hammer

drawn to the same scale as FIGURE 6 but taken from the lower left hand corner of FIGURE 2.

I claim:

The ornamental design for an impeller hammer for a silo unloader or the like, as shown.
